Primary Examiner — Ricky Pham

(57) **CLAIM**

The ornamental design for an immersion blender, as shown and described.

DESCRIPTION

FIG. 1 is a top perspective view of an immersion blender; FIG. 2 is a bottom perspective view of the immersion blender of FIG. 1; FIG. 3 is a first side elevational view of the immersion blender of FIG. 1; FIG. 4 is a second side elevational view of the immersion blender of FIG. 1; FIG. 5 is a third side elevational view of the immersion blender of FIG. 1; FIG. 6 is a fourth side elevational view of the immersion blender of FIG. 1; FIG. 7 is a top plan view of the immersion blender of FIG. 1; and, FIG. 8 is a bottom plan view of the immersion blender of FIG. 1. The broken lines are for illustrative purposes only and form no part of the claimed design.

1 Claim, 4 Drawing Sheets
